CHARLES A. BUTCHER, OF FOREST HILLS, PENNSYLVANIA, ASSIGNOR TO WESTINGHOUSE ELECTRIC & MANUFACTURING COMPANY, A CORPORATION OF PENNSYLVANIA

SHORT-CIRCUIT DETECTOR

Application filed May 17, 1928. Serial No. 278,395.

This invention relates to protective systems and, more particularly, to protective systems for direct-current distribution circuits such as are employed to supply energy to railway systems.

In my copending application, Serial No. 81,858, filed on January 16, 1926, I have disclosed a protective system involving the use of a direct-current relay which is energized in accordance with the rate, duration and direction of changes of current in a direct-current transmission system.

The copending application of Roy J. Wensley, Serial No. 672,829, filed November 15, 1923, and assigned to Westinghouse Electric & Manufacturing Company, discloses a protective system which also operates in response to the rate and direction of changes of current in a direct-current distribution system.

The principal object of this invention is to improve upon the systems disclosed in the above mentioned applications and to provide a protective system for direct-current distribution systems which will operate to isolate faulty sections of such systems upon the occurrence of faulty conditions therein.

Another object of this invention is to provide a protective system which will be unaffected by the occurrence of legitimate overloads.

A further object of this invention is to provide a protective system capable of discriminating between short circuits and legitimate overloads, even though the latter be of higher absolute value than the former, and regardless of whether the rate of current increase is greater or less.

Another object of this invention is to provide a protective system which will operate promptly to isolate a faulty portion of a distribution system without interrupting service on the remaining portions thereof.

A still further object of this invention is to provide a protective system combining the quick response of a solenoid-and-plunger type relay for isolating a circuit section on the occurrence of a nearby fault, and the inherent, inverse time characteristic and the ballistic effect of a galvanometer or D'Arson-

val type relay, for responding to distant faults.

In accordance with my invention, I provide a protective system including an instantaneously responsive relay of the solenoid-and-plunger type which is designed to effect the opening of a circuit-breaker upon the occurrence of a short-circuit near the supply source. I provide also an inductively damped galvanometer relay having an inverse time characteristic which responds to distant faults after a time dependent upon the rate and duration of increments in the short-circuit current, for further controlling the circuit-breaker.

Further objects and advantages of the system of my invention will become apparent as the description thereof proceeds.

For a complete understanding of this invention, reference is made to the accompanying drawings, in which,

Fig. 1 is a diagram illustrating the circuits and apparatus employed in one modification of my invention.

Fig. 2 is a circuit diagram of the usual direct-current distribution circuit in connection with which the system of my invention finds its principal field of utility.

Fig. 3 illustrates graphically the variations with time of the short-circuit current in the distribution system and the current in the relay of the protective system of my invention; for the fault condition shown in Fig. 2;

Fig. 4 is similar to Fig. 3, but illustrates a different condition of the distribution system; and

Fig. 5 illustrates another modification of my invention which is especially designed to afford protection against the conditions illustrated in Fig. 4.

Referring particularly to Fig. 1, a direct-current distribution circuit 10 is adapted to be connected, by a circuit breaker 11, to any suitable source of supply (not shown). The circuit breaker 11 is adapted to be closed by the energization of its closing coil 12 which may be connected to an auxiliary source of current 13 by the closing of switch 14, which may be controlled automatically as well as manually. The circuit-breaker 11 is pro-

vided with a latching mechanism 11', which, when the circuit breaker is closed, maintains it in that position so that the closing coil 12 may be de-energized without causing the breaker to open. A tripping coil 16 is provided to positively unlatch the circuit breaker 11 upon the occurrence of predetermined conditions, whereby the breaker is opened immediately by a spring 12', or other suitable means.

10 Connected in the circuit between the current source and the circuit breaker 11 is a series or impulse transformer 17. A transient voltage is induced in this impulse transformer whenever a value of the current in the feeder circuit changes, the direction of the voltage being dependent upon the direction of the change of current. For controlling the circuit-breaker 11, I provide protective relays 20 and 21 having operating coils 18 and 19, respectively, connected in series to the impulse transformer 17. These operating coils are energized by the transient current resulting from the voltage induced in the impulse transformer 17 when the magnitude or direction of the current in the circuit 10 changes.

15 A variable inductance 18'' is connected in series with the moving coil 18 of the relay 20 for a purpose which will appear herein-after.

20 The relay 20 is a galvanometer relay of the D'Arsonval type and consists of a magnetic circuit 22 with which the operating coil 18 cooperates. The magnetic circuit 22 may be either that of an electromagnet or a permanent magnet and, as shown, is an electromagnet having its winding connected to the source 13. The moving coil 18 actuates a contact arm 23 which is adapted to bridge the contacts 24 to perform a function which will be described later.

25 The moving coil 18 of the relay 20 is wound upon an aluminum frame which constitutes an inductive damping means as well as a mechanical support for the coil.

30 It is well known characteristic of devices of the galvanometer type that the rotation of the moving coil is dependent upon both the magnitude and the duration of the energizing current. Thus, in the system of my invention, the relay 20 functions in response both to the average rate and to the duration of changes of the current in the distribution circuit.

35 In addition to the relay 20, I provide also the relay 21 which is a simple solenoid-and-plunger relay having a moving contact 25 adapted to bridge the fixed contacts 26. The operating coil 19 of the relay 21 is energized by the same current which traverses the moving coil 18 of the relay 20. The moving element 25 of the relay 21 is small and light in weight, and its operation, therefore, is almost instantaneous. The relay 21 func-

tions largely in response to the peak value of the energizing current or, in other words, in the system of my invention, substantially to the average rate of change of the current in the circuit 10. Besides the operating coil 19, the relay 21 is provided with a polarizing coil 27 which is continuously energized from the source 13. The function of the polarizing coil 27 is to prevent operation of the relay 21 upon the occurrence of a decrease in the current in the circuit 10, and this object is accomplished by so connecting the winding 27 that its magnetic effect aids that of the operating coil 19 when the current in the circuit 10 increases but opposes the magnetic effect of the coil 19 when the load current decreases.

100 An auxiliary relay 28 has its operating coil connected in a circuit including the contacts 24 of the relay 20 and contacts 26 of the relay 21, which are in parallel therewith, an auxiliary front contact 29, which is closed when the circuit-breaker 11 is closed, and the current source 13. When the relay 28 is energized, its contact 30 is closed and completes a circuit from the source 13, through the contact 29 on the circuit-breaker, the contact 30 of the relay 28, the circuit-breaker trip coil and thence to the source 13. The operation of the relay 28 also completes a 105 circuit in parallel with the contacts 24 and 26 so that its coil is maintained energized independently of the engagement of the contacts of relays 20 and 21 until the circuit is opened at contact 29 which opens when the tripping coil 16 is effective to cause the opening of the circuit-breaker 11.

110 The modification of my invention already described will operate successfully to discriminate between short circuits and legitimate load currents even though the latter are greater than the former in absolute value and regardless of whether the rate of current increase is greater or less. This method of operation results from the fact that the 115 system of my invention responds, not to the maximum value of current increments in the load circuit, but to both the average rate of change of current and to the duration of such change.

120 As already stated, it is the function of the relay 20 to respond to distant faults which cause the current in the load circuit to increase with a comparatively slowly-rising characteristic. This slowly-rising characteristic is 125 a result of the relatively high resistance and inductance in the load circuit when the fault is located at a distance from the source. The relay 20, because of its ballistic characteristic, is actuated in response to a slowly-rising current increment which has a peak value lower than that required to effect the operation of the relay 21, through the energization of its operating coil 19, by the voltage induced in the impulse transformer 17. 130

The relay 21, on the other hand, serves to isolate severe short-circuits which are caused by faults occurring relatively close to the supply source. In this case, the resistance and inductance of the circuit are low, and the average rate of rise of short-circuit current is much greater than that of any legitimate load increment. The relay 21 is designed to operate in response to such conditions and will actuate its contact 25 almost instantaneously upon the occurrence of such a short-circuit.

The relay 20 also operates on near-by short-circuits but only after a definite time delay inherent in the relay because of its inductive damping. The principal function of the relay 21 is to cause the tripping of the breaker 11 substantially instantaneously in installations in which the fault current is reduced or interrupted by the opening of a high-speed circuit-breaker in the feeder circuit.

The protective system of my invention, therefore, operates to guard against short-circuit conditions at any point in the distribution system. False operation, as a result of load increments, is prevented by the current-time characteristic of such a circuit condition, in response to which the protective system of my invention does not operate.

As already stated, the relay 20 operates not only in response to the average rate of change of current in the circuit 10, but also in response to the duration of such change.

Because of the fact that there is always a difference in the characteristics of short-circuits and normal load increments, and because the system of my invention may be adjusted to operate under a wide range of varying conditions, I am enabled to detect and isolate short-circuits, and, at the same time, avoid interruption of service on the load circuit upon the occurrence of a legitimate overload, even though the latter is much greater in absolute value than the former, whatever the constants or characteristics of the system may be.

As a further means for preventing the relay 20 from responding to a sharply rising current increment, where such operation is desirable, I employ a non-inductive shunt 18' connected across the moving coil 18 of the relay 20. Although the inductance of the winding of the moving coil 18 is slight, it is large in comparison with that of the non-inductive shunt 18'. When a transient voltage is induced in the impulse transformer 17, as a result of a sharply rising increment in the load current, the impulse current in the relay circuit will divide between the resistor 18' and the coil 18 in inverse proportion to their impedances. Thus, only a portion of the impulse current passes through the coil 18, while the remainder passes through the resistor 18'. This further reduction in the current through the operating coil of the relay 20, upon the occurrence of a high-rate incre-

ment in the load current, tends to prevent the relay from operating when the load current increases at a very high rate. When the current increase is of a slowly rising characteristic, however, the impulse current divides between the coil 18 and the resistor 18' substantially in inverse proportion to the resistances of these elements, and the coil receives a greater portion of the impulse current than in the case previously described, so that the relay 20 will operate to bridge its contact members 24 in response to a slowly-rising current increment but will be affected only slightly by a current increment of sharply-rising characteristic. This division of the current from the impulse coil 17 may be controlled by adjusting the variable inductance 18'' in series with the moving coil 18 of the relay 20.

For a further explanation of the operation of my protective system, reference is made to Fig. 2 illustrating a direct-current distribution system in which my protective system is found useful.

In Fig. 2, sections of a trolley wire or third rail are indicated at 35, 36 and 37. These sections of trolley wire may be energized from suitable sources, such as the generators 38 and 39, through circuit-breakers 40, 41 or 42, 43 which connect the generators 38 and 39 to sections 44, 45 and 46 of a feeder cable. The feeder sections are connected to the trolley at intervals by the taps 47. It is to be noted here, in passing, that a third rail conductor will have a considerably greater inductance than a copper trolley wire or feeder conductor.

Let it be assumed that a short circuit occurs at A. This fault will be fed from the two sources 38 and 39, through the feeder section 45, the trolley tap B and the trolley circuit BA. The heavy current from the source 39 results in such a high IR drop in the trolley circuit BA as to limit materially the current which can be supplied from the source 38, through the breaker 41. As soon as the breaker 42 opens as a result of the operation of the relay 21 of Fig. 1, the current through the breaker 41 rises to the same final value as that to which it would have risen had the breaker 41 been feeding the short circuit A alone. The current through the breaker 41 thus rises to its final value in two steps which may be seen in Fig. 3, which illustrates graphically the conditions existing in various portions of the distribution circuit upon the occurrence of a fault, such as that at A.

In Fig. 3, the curve 50 illustrates how the current supplied by the source 38 to the fault A would increase if no current were supplied to the fault by the source 39. The curve 51 illustrates the impulse current which would be induced in the impulse transformer 17 by a current increment of the characteristic

illustrated by the curve 50. When the fault A is fed from both sources 38 and 39, however, the current supplied by the source 38, through the breaker 41, rises in the manner 5 illustrated by the curve 52 in accordance with the foregoing explanation. The current increase takes place in two steps and, consequently, two separate impulses 53 and 54 are induced in the transformer 17.

13 It is apparent that any device which functions only in response to average rate of rise of feeder current or, in other words, to the peak value of the impulse current, must be set to trip on the smaller impulses 53 and 13 54. This setting, however, would be low enough to cause a relay, such as the relay 21, to be operated by legitimate load increments having a peak value within the capacity of the generating equipment. In the system of 20 my invention, however, the relay 21 may be set to respond only to impulse currents of the peak value of that shown by the curve 51, and the relay 20 may be relied upon to operate when the load current increases in 25 accordance with the curve 52. This relay, because of its ballistic characteristic, adds the effects of the two impulses 53 and 54 and bridges its contact members 24 to cause the opening of the circuit-breaker.

20 For the purpose of distinguishing between short-circuits and load increments of closely similar characteristics, I have devised a modification of my invention.

Referring to Fig. 4, let it be assumed that 35 a fault current has the characteristic shown by the curve 60, and that a legitimate load increment has a characteristic, such as that shown by the curve 61. Since the curves 60 and 61 coincide between the origin and the 40 point 62, it is obvious that any means for discriminating between the two conditions must be set to operate at a time later than that of the point 62.

The means which I have provided for discriminating between legitimate loads and short circuits of closely similar characteristics is shown in Fig. 5, which, in general, is similar to the circuit of Fig. 1. The difference consists in that a compound winding 71 is 50 provided for the relay 20, being connected in series with a resistor 73 across a non-inductive shunt 74. An inductance 72 is connected in series with the shunt 74 and both are shunted by a resistor 75. In all other respects, the 55 circuit of Fig. 5 is identical with that of Fig. 1 and operates in a similar manner to cause the tripping of the circuit-breaker 11 under appropriate conditions.

By the provision of the winding 71, the 60 inductance 72, and the shunts 74 and 75, however, the operation of the relay 20 is made to depend, not only upon the rate and duration of changes in the load current, but also upon its magnitude. The inductance 72 prevents the compound winding 71 from becom-

ing fully energized until a time at which the characteristics of the short circuit and the legitimate load diverge, by absorbing the greater portion of the voltage drop across the shunt 75 so long as the load current rises at a relatively rapid rate. Because of the added flux induced in the magnetic circuit of the relay 20 by the compound winding 71, when it does become energized, a greater torque is exerted on the moving coil 18 by the occurrence of a fault having a characteristic illustrated by the curve 60 than by the occurrence of an overload having a characteristic illustrated by the curve 61. The torque on the moving element of the relay is proportional to the area enclosed by the curves illustrating the current through the moving element under the two conditions. These curves are illustrated at 80 and 81 in Fig. 4.

The curve 80 illustrates the current passing through the moving coil 18 of the relay 20 when a short-circuit having the characteristic illustrated by the curve 60 occurs on the circuit, while the curve 81 illustrates the current passing through the relay winding as a result of a load increment having the characteristic illustrated by the curve 61. The curve 80 obviously encloses a much greater area than the curve 81 and, therefore, the occurrence of a short-circuit exerts a much stronger turning impulse on the moving element of the relay 20 than does the occurrence of a legitimate overload of a similar rising characteristic. The distinguishing feature of the two conditions resides in the fact that, when a legitimate load is placed on the circuit, although the current increment may be of nearly the same characteristic as a short-circuit, it continues to rise for a limited period only, and then starts to droop because of the effect of the counter-electromotive force developed by the load devices, such as railway motors, whereas, under short-circuit conditions, the current increases steadily to its final value, at a rate dependent on the circuit constants.

It is apparent from the curves in Fig. 4 that the turning impulse on the moving coil of the relay 20 is considerably greater, on the short-circuit condition, after the time at which the curves 60 and 61 diverge, than would be the case if there were no compounding of the field flux of the relay.

From the foregoing description, it will be 120 apparent to those skilled in the art that the system of my invention provides complete protection for direct-current distribution circuits and that, while it causes prompt isolation of faulty portions of such circuits, it 125 does not operate as a result of legitimate load increments, even though the absolute value of the latter is greater than that of the former.

I am aware that it has been previously proposed to make use of a galvanometer relay 130

for direct-current distribution-system protection and that it has also been suggested to use a polarizing plunger type of relay, but I believe I am the first to combine these devices into a single protective system having the novel characteristics and advantages hereinabove pointed out.

Since it will be obvious to those skilled in the art that the system disclosed herein may be changed in many respects, I do not intend 10 my invention to be limited to the specific modifications disclosed, except as necessitated by the appended claims.

I claim as my invention:

- 15 1. In a protective system for a direct-current distribution system, a circuit-interrupter for disconnecting a faulty section from a supply source, means for controlling the operation of said interrupter including a relay operative in accordance with the average rate of change of current in the system and a relay responsive to both the average rate and duration of such change.
- 20 2. The combination with a direct-current distribution system, a circuit-interrupter therein for isolating portions thereof, of means for controlling the operation of the circuit-interrupter including a relay responsive to the average rate of current rise in said 25 system and a relay operative in response to the magnitude of the current and the rate and duration of such increase.
- 30 3. In a protective system for a direct-current distribution circuit, a circuit-interrupter in said circuit and means for controlling said interrupter including a solenoid relay instantaneously responsive to the average rate of change in the current in said circuit, and a ballistic relay responsive, after a time delay, 35 to the average rate, the duration and the direction of such change.
- 40 4. In a protective system for a direct-current circuit, a circuit-interrupter therein and means for controlling said interrupter including a relay responsive instantaneously to brief, high-rate current changes in said circuit and a relay responsive after a time delay to extended, low-rate changes, whereby said 45 interrupter is opened on the occurrence of short-circuits but not on legitimate overloads, regardless of the relative absolute values of the current under such conditions.
- 50 5. A relay system for protecting a circuit, capable of discriminating between legitimate overloads and short-circuits, comprising a 55 circuit-interrupter in said circuit, a relay responsive to the average rate of rise of the current in said circuit and a relay responsive to the average rate, the duration and the magnitude of such rise, and means responsive to the operation of either of said relays to cause the opening of said interrupter.
- 60 6. A protective system for a direct-current circuit comprising a circuit-interrupter and 65 an impulse transformer connected in said

circuit, relays having windings connected across said transformer, one of said relays being responsive instantaneously and another being responsive after a time delay, and means controlled by said relays to cause the 70 opening of the interrupter.

7. A protective system for a direct-current circuit comprising a circuit-interrupter and an impulse transformer connected in said circuit, an instantaneously responsive solenoid 75 relay and a galvanometer relay of the D'Arsonval type responsive after a time delay, said relays having their windings connected across said impulse transformer, and means controlled by said relays for causing 80 the opening of said interrupter.

8. A protective system for a direct-current circuit comprising a circuit interrupter and an impulse transformer connected in said circuit, an instantaneously responsive solenoid 85 relay and an inductively damped galvanometer relay having a moving coil connected with the coil of said solenoid relay across the impulse transformer and a fixed coil adapted to be connected to a substantially constant-voltage source of current, and means controlled by said relays for opening said 90 interrupter.

9. A protective system for a direct-current circuit comprising a circuit interrupter and an impulse transformer connected in said circuit, a plunger type relay having a biasing coil and an operating coil and a ballistic galvanometer relay having a coil connected with said operating coil across said impulse 100 transformer, said biasing coil being adapted to be connected to a constant-voltage source so that its magnetic effect aids that of the operating coil when the latter is energized by an increase in the current in said circuit, and neutralizes the effect of the operating coil when the latter is energized by a decrease in the current in said circuit, and means controlled by said relays for opening the 105 interrupter.

10. A protective system for a direct-current distribution circuit comprising a circuit-interrupter and an impulse transformer connected in said circuit, a plunger relay having an operating coil, a moving contact and a biasing coil, and an inductively damped ballistic galvanometer relay having an operating coil, a moving contact and a polarizing coil, the operating coils of said relays being connected in series across said impulse transformer, the biasing and polarizing coils being adapted to be energized so that upon an increase in the current in the circuit, the relay contacts are actuated in one direction, and upon a decrease in said current, the contact of said first mentioned relay is unaffected and the contact of the galvanometer relay moves in a reverse direction, and means controlled by said relays for opening the 115 interrupter.

11. A protective system for a direct-current circuit comprising a circuit-interrupter and an impulse transformer connected in said 120

11. In a protective system for a direct-current circuit, the combination with a circuit-interrupter and an impulse transformer connected in said circuit, of means for controlling said interruptor comprising a relay of the D'Arsonval galvanometer type having a fixed coil adapted to be energized constantly and a moving coil connected to said impulse transformer, a moving contact actuated by said moving coil and a non-inductive shunt in parallel with said moving coil, and means controlled by said relay for opening said interrupter.

12. The combination, in a protective system, with a distribution circuit, a shunt, an impulse transformer and a circuit-interrupter therein, of a ballistic relay of the D'Arsonval galvanometer type having a magnetic circuit, and a moving coil cooperating therewith connected to said impulse transformer, a non-inductive shunt connected across said coil, means for exciting said magnetic circuit comprising a coil connected across said shunt, and a coil adapted to be constantly energized, and means controlled by said relay for opening said interrupter.

13. The combination, in a protective system, with a distribution circuit, an inductance, a shunt, a series transformer and a circuit-interrupter in said circuit, of an inductively-damped galvanometer relay having fixed and moving coils, the moving coil being connected to said transformer and in parallel with a non-inductive resistor, one of said fixed coils being adapted to be connected to a constant-voltage current source, and another of said fixed coils being connected across said shunt.

14. The combination with a direct-current distribution system, a circuit-interrupter therein for isolating portions thereof, of means for controlling the operation of the circuit-interruptor including means responsive to the average rate of rise of current in said system and means operative in response to the magnitude of the current and the rate and duration of such increase.

In testimony whereof, I have hereunto subscribed my name this 12th day of May, 1928.

CHARLES A. BUTCHER.
